UNITED STATES PATENT OFFICE.

WILBUR S. LEWIS, OF CLEVELAND, OHIO.

PERMANENT-WAVING APPARATUS.

Application filed November 19, 1926. Serial No. 149,340.

My invention relates to permanent waving apparatus and relates particularly to permanent waving apparatus of the type wherein a wound strand of hair is subjected to the combined effects of heat and hair-treating materials to effect the waving of the hair strand.

In the art of permanent waving in the past, there has been considerable misunderstanding and lack of knowledge as to the proper length of time, under different conditions of applied heat, that human hair sought to be "waved" should be subjected to steaming during a permanent waving process, and heretofore, so far as I am aware there has been no means of determining the heat conditions operative upon the strand of hair during the heating operation of the waving process.

In permanent waving processes to which my present invention is applicable, it is the usual practice to first moisten the hair with a softening solution, and then gather the hair into a plurality of hair strands each of which is then wound around a separate curled rod. The wound strands are then stretched lengthwise upon the rods, and, after being secured thereto, are wrapped with a pad of absorbent material which is usually previously treated with a hair-treating solution, which may be the same as that with which the hair was moistened. The wound strand of hair is then placed in a container to enclose the same and heat is applied through the walls of the container to effect what has come to be known as the "steaming" process, whereby the liquid portions of the hair-treating materials are caused to take the form of steam and effect such a softening of the hair strands that stretching of the same to effect permanent waving of the strand may be accomplished. Usually an aperture is provided through an end or a wall of the container for the escape of the gases comprising the steam, and if the heating is carried on for a sufficient length of time, all of the liquid within the container will have been converted into steam and the temperature within the tube will rise above the boiling point of water, 212 degrees Fahrenheit, and above which temperature I have found injury to the hair occurs.

An object of my invention, therefore, is to prevent injury to the wound strand of hair during the heating operation of a waving process.

Another object of my invention is to permit the employment of an operator of less experience than that heretofore required to perform the hair waving operation, at the same time providing against injury to the hair of the patient during the heating operation.

Another object of my invention is to enable the operator and the patient operated upon, during hair waving process, to know at all times the degree of heat to which the hair of the patient is at the time being subjected.

Another object of my invention is to provide a thermal responsive means of such a form as to be capable of inclusion within the container of a hair waving apparatus in a position such as not to interfere with the usual hair waving process, and at the same time to be disposed in contact with the strand of hair operated upon adjacent the base of the strand and co-operating with the container in such a way that an effective seal is had against the undue escape of gases from the container during the process.

Other objects of my invention and the invention itself will become apparent as the following description of a specific embodiment of my invention progresses, and in which description reference will be had to the accompanying drawings illustrating the said embodiment.

Referring to the drawings:

Fig. 1 shows a perspective view of an embodiment of my invention during the assembling operation while the wound strand of hair is being enclosed prior to the "steaming" operation of a waving process.

Fig. 2 illustrates, in like view, portions being shown as broken away to reveal inner parts of the container and parts enclosed thereby, including thermal responsive means ready for the "steaming" operation of a waving process.

Fig. 3 is a view, in elevation, of the hair waving apparatus during the "steaming" process, and with a pyrometer indicator illustrated as in operation to indicate the degree of heat to which the hair is being subjected.

Fig. 4 is a view of the thermal responsive means, circuit conductors, and pyrometer, in electrical circuit but prior to inclusion with a wound strand of hair, the heating of which is to be indicated by the pyrometer.

Fig. 5 is a section taken on the line 5-5

of Fig. 4, and enlarged to twice the size of the other figures;

Fig. 6 is a chart whereby a curve traversing ordinate and abscissæ lines of reference indicates, at successive intervals of time, the progressively increasing heat effective upon the strand of hair being treated.

Referring now to all of the figures of the drawing, in all of which like parts are designated by like reference characters, at 1 1 show a curler rod comprising an outer tube 2 and an inner rod portion 3 telescoped within the tube and secured against longitudinal movement relatively thereto by virtue of an inwardly extending rib 4 of the tube projecting within a corresponding annular groove on the exterior surface of the rod. According to the construction illustrated in my co-pending application, Serial No. 109,077, filed May 14, 1926, the rod and tube just are therein illustrated and described as relatively rotatable in order that the strand of hair, shown at 5, wound upon the tube 2 may be tightened in accordance with the disclosure of the said prior application. The hair may be secured to the bifurcated end 6 of the rod by tying it with a cord 7 thereto and the hair is then moistened by a hair-treating solution and enclosed by a moistened flannel ribbon 8 which completely covers and encloses the strand of hair and the curler rod, except for the projecting ends thereof. I then enclose within the wrapping 8 of moistened flannel, or like material, and which may be impregnated with the same kind of hair-treating solution as employed to moisten the hair, a thermal responsive element 9 comprising a thermal junction of two electrically dissimilar metals, such as cadmium and chromium, and extending from each of the joined metals I provide electrical circuit conductors 11 and 12 which lead to an electrical current indicating instrument, which together with the thermo-couple and circuit conductors is commercially known as a pyrometer, the indicating instrument being shown at 13 and adapted to indicate, by movements of an indicating needle 14 over a dial scale 15, the amount of electrical current traversing the electrical circuit conductors 11 and 12, by virtue of the current set up by heating of the thermo-couple 9 of dissimilar metals, in accordance with well known electrical principles.

I preferably graduate the scale 15, as illustrated, dividing it into two parts, the left-hand portion 16 being relatively dark in color and of some such color as blue or green, and the right-hand portion of the dial 17 being relatively light in color and preferably with some such inscription as "dry heat" "or danger," the junction between the two portions of the scale being indicated by a heavy red or black line 18 and having an inscription such as "steam", as shown in

the drawing, disposed closely adjacent to such line 18. Of course, various other manners of marking the scale may be employed, but it is very desirable that the scale be so marked as to emphasize departures from a temperature of and below 212 degrees Fahrenheit, and toward higher temperatures.

The thermo-couple 9 being placed within the wrapping 8 and the portion of the circuit conductors 11 and 12 extending therefrom along the wound strand of hair, and preferably in contact therewith, being likewise enclosed for a considerable length, the tubular container 19 is then telescoped over the wound and wrapped strand of hair and thermo-couple with leading-in wires for the thermo-couple, and the sealing of the end portions of the tubular side walls against the wound strand of hair being accomplished at 20 and 21, in any suitable manner, such as by crimping inwardly the material of the tubular container and holding it in such inward crimped condition whereby escape of steam and gases is effectually restricted and substantially prevented through the ends of the tube.

Although this sealing may be accomplished in various ways, I preferably accomplish the same by employing a tube having projecting portions 22 and 23, which, as described and shown, are inwardly crimped at 20 and 21, comprising a sheet of metal foil, such as aluminum foil, and which is made of sufficiently plastic, non-elastic material that it will take a "set" and will not restore by its resiliency to a non-crimped position. I find that aluminum foil having a thickness of .0016" possesses the necessary qualities to effect a good seal, by crimping of the tubular foil, for all practical purposes. I preferably make the tube 19 of a layer of aluminum foil with exterior and interior layers of thin paper all rolled together into the form of a tube, the paper being of shorter length than the foil, which projects by portions 22 and 23 beyond the ends 24 and 25 of the paper portion of the tube.

At 26, closely adjacent the end of the tube most closely adjacent the scalp of the patient, I provide a small aperture for the escape of steam and gases from the interior of the tube 19 to atmosphere. In practice, the opening 26 is near the bottom end of the tube, the top end of the tube being that end from which projects the circuit conductors 11 and 12 and which, in this portion of the circuit conductors, are enclosed by a fabric covering 27 which extends from a plug and socket connector 28 to the thermo-couple 9. The circuit conductors 11 and 12 in the portion 27 of their length are preferably of resilient stiff wire material, such as bronze or the like. The plug and socket connector 28 of the circuit conductors 11 and 12 lead to the indicator 13 from the portion 27 extend-

ing within the container 19 under the wrapping 8. The portion 27 of the leading-in wires 11 and 12 is preferably flattened in form, with the stiff leading-in wires arranged 5 side by side and the fabric covering enclosing the parallel leading-in wires, as illustrated best in Fig. 5. While the exterior dimensions of the enclosing leading-in wires may be varied, I find that very good results are secured 10 when the dimension "a", Fig. 5, is as great as $1/10$ ", and the dimension "b" is as great as $1/5$ ". These dimensions are taken over the exterior of the tubular fabric covering 30 for the circuit conductors 11 and 12. 15 The thermo-couple 9 is placed closely adjacent the scalp end of the heated wound hair, that is closely adjacent the end 6 of the curler rod and preferably is placed in intimate contact with the hair wound upon 20 the curler rod.

The position of the heating element is indicated by dotted lines, Fig. 2 at 32, the heating element being annular in form, elongated and telescoped over the exterior 25 walls of the tube 19, its bore being somewhat larger than the diameter of the walls. In practice, I secure very good results by providing only one pyrometer means, comprising the indicator 13, circuit conductors 30 11 and 12, and thermo-couple 9, with leading-in wire portions of the conductors 11 and 12, 27, and place the thermo-couple within one of the steaming tubes of a large number of steaming tubes, such as 32 or 44, 35 which are simultaneously in use to effect permanent waving of the hair of the patient. I find that the heating effects within one tube are indicative of the heating effects in all of the tubes wherein steaming is initiated 40 simultaneously with that in the first tube. The flattened shape of the insulated leading-in wires permits the same to be wound in with the hair and still permit the ready telescoping of the tubular container 45 19 over the wrapped wound hair.

Fig. 6 shows a chart indicating the temperatures according to the Fahrenheit scale actually observed during a sample hair waving operation wherein the apparatus of my 50 invention was actually used. It will be seen that after a certain period of time following initiation of the heating operation, such as 12 minutes, the temperature starts to rise above 212 degrees, and I find, in practice, 55 that when the temperature operative upon the hair does so rise above 212 degrees, the hair is damaged and will subsequently be brittle and break.

Having thus described my invention in a 60 single embodiment, I am aware that numerous and extensive departures may be made from the embodiment herein illustrated and described, but without departing from the spirit of my invention.

65 I claim:

1. In a hair permanent waving apparatus, the combination with a curler rod upon which is wound a strand of hair, of a thermo-couple element disposed in physical contact with the wound strand, of a wrapper 70 enclosing the wound strand of hair and element, means to heat the wound strand of hair, in the presence of moisture, through the walls of the wrapper, an electroresponsive indicator means disposed exteriorly of 75 the tube, and electrical circuit conductors interconnecting the said element and the said indicator means.

2. In a permanent waving apparatus for hair, the combination with a curler rod upon 80 which a strand of hair is adapted to be wound, of a thermo-couple element of a fabric wrapper enclosing the wound strand of hair and element with the element in contact with the hair, a steaming tube telescoped over the wrapped strand of hair and element, means to heat the wound strand of hair, in the presence of moisture, through the walls of the tube and through the wrapper, circuit conductors leading from the 85 thermo-couple element and exteriorly of the tube and an exterior electroresponsive indicating means connected to the thermo-couple element by said circuit conductors, said indicator means responsive to the electrical 90 current set up by heating of the thermo-couple to indicate the degree of heating of the strand of hair.

3. In a hair permanent waving apparatus, the combination with a curler rod around 100 which a strand of hair may be wound, a pair of circuit conductors, a thermo-couple element joining the conductors at an end of each conductor, an insulating sleeve telescoped over the conductor, said thermo-couple element projecting beyond the end of the sleeve, of a wrapper of fabric material enclosing the wound strand of hair, an end portion of said electrical circuit conductors and the thermo-couple, adapted to hold the 105 thermo-couple in intimate contact with the wound strand of hair, and means to heat the wound strand of hair, in the presence of moisture, through the walls of the wrapper.

4. In a hair permanent waving apparatus, the combination with a curler rod around 115 which a strand of hair may be wound, a pair of circuit conductors, a thermo-couple element joining the conductors at an end of each conductor, an insulating sleeve telescoped over the conductor, said thermo-couple element projecting beyond the end of the sleeve of a wrapper of fabric material enclosing the wound strand of hair, an end portion of said electrical circuit conductors 120 and the thermo-couple adapted to be held in intimate contact with the wound strand of hair, and means to heat the wound strand of hair, in the presence of moisture, through the walls of the tube, the portion of the 125 130

circuit conductors enclosed by the wrapper being of relatively resilient material.

5. In a hair permanent waving apparatus, the combination with a curler rod around 5 which is wound a strand of hair, a wrapper enclosing the wound strand of hair, a tube telescoped over the strand, means to heat the wound strand by heat transmitted exteriorly of the tube through its walls and 10 through the wrapper, thermo-responsive means adapted to be placed within the wrapper adjacent the hair strand, indicating means adapted to be disposed remotely of the tube and exteriorly thereof, and means 15 adapted to communicate the effect of temperature variations affecting the thermo-responsive means to said indicator, to cause it to indicate the temperature of the thermo-responsive means, a portion of the inter- 20 connecting means forming a support for the thermo-responsive means and adapted to be bound within the wrapper therewith.
6. In apparatus for "permanent" waving, the combination with a steaming tube 25 for enclosing a strand of hair to be heated from an extraneous source of heat, of thermal-indicating means for indicating the temperature to which the enclosed strand is subjected during the waving process, said 30 indicating means comprising heat responsive means projected into the interior of the tube next adjacent the hair strand, an indicator disposed exteriorly of the steaming tube, and means communicating the effect of heat 35 upon the responsive means to the indicator, said last named means being projected through an end of the steaming tube and sealed therewith to prevent the egress of heated vapors thereat.
- 40 7. The method of permanently waving hair which consists of heating the hair together with moisture, indicating the temperature existing at the hair, and discontinuing the heating when the temperature at the 45 hair exceeds that of the evaporation of the moisture.

8. The method of permanently waving hair which consists of heating the hair together with moisture, indicating the temperature existing immediately at the hair, and controlling the application of heat in 50 accordance with said indicated temperature.

9. The method of permanently waving

hair which consists of wrapping the hair upon a rod, enclosing the hair with moisture 55 within a chamber, indicating the temperature existing at the hair, heating the hair and moisture while in the chamber, gradually evaporating the moisture, and discontinuing the application of heat when the 60 temperature indicated exceeds that required for evaporation of the moisture.

10. The process of permanently waving hair which consists of gathering the hair into a plurality of strands, winding each 65 strand upon a rod, and subjecting the same to moisture, applying heat to all the moistened strands simultaneously, indicating the temperature existing immediately at the hair of one strand, and discontinuing the applica- 70 tion of heat from all the strands upon the indication of a temperature exceeding that required for evaporation of the moisture.

11. The process of permanently waving hair which consists in gathering the hair into a 75 plurality of separate strands, wrapping each strand upon a separate rod, enclosing each rod and strand within a separate chamber with moisture, indicating the temperature existing immediately at the hair of one 80 strand, applying heat simultaneously to all the chambers and evaporating moisture therein, and discontinuing the application of heat to all the chambers when the temperature indicated exceeds that required for 85 evaporation of the moisture.

12. In apparatus for "permanent" waving, the combination with means for enclosing a strand of hair to be heated from an extraneous source of heat, of thermal-indicating means for indicating a critical temperature to which the enclosed strand is subjected during the waving process, said indicating means comprising heat responsive means projected into the interior of the enclosing 95 means next adjacent the hair strand, an indicator disposed exteriorly of the strand enclosing means, and means communicating the effect of heat upon the responsive means to the indicator, said last named means being 100 projected through an end portion of the enclosing means and sealed therewith to prevent the egress of heated vapors thereat.

In testimony whereof I hereunto affix my signature this 12 day of October, 1926.

WILBUR S. LEWIS.
